UNITED STATES PATENT OFFICE

149,453

DESIGN FOR A CONTROL HANDLE FOR LINE
CONTROLLED MODEL AIRCRAFT

Victor Stanzel, Schulenburg, Tex.

Application January 24, 1947, Serial No. 136,359

Term of patent 14 years

(Cl. D34—5)

To all whom it may concern:

Be it known that I, Victor Stanzel, a citizen of the United States of America residing at Schulenburg, in the county of Fayette, State of Texas, have invented a new, original, and ornamental Design for a Control Handle for Line Controlled Model Aircraft, of which the following is a specification, reference being had to the accompanying drawings, forming a part thereof.

Figure 1 is a plan view of the control handle for line controlled model aircraft showing my new design.

Figure 2 is a side elevation thereof, and
Figure 3 is a front end elevation thereof.

I claim:

The ornamental design for a control handle for line controlled model aircraft, as shown.

VICTOR STANZEL.
